(57) **CLAIM**

The ornamental design of a dust cover for an upright vacuum cleaner, shown and described.

DESCRIPTION

FIG. 1 is a perspective view showing in full line the dust cover for an upright vacuum cleaner of the present invention on an upright vacuum cleaner shown in phantom line;

FIG. 2 is a front elevational view thereof;

FIG. 3 is a top plan view thereof;

FIG. 4 is a bottom plan view thereof; and,

FIG. 5 is a right side elevational view thereof, the left side being a mirror image.

The details shown in broken lines in FIGS. 1 and 4 are for illustrative purposes only and form no part of the claimed design.
